UNITED STATES PATENT OFFICE.

WILLIAM C. MOLER, OF CLAGGETT'S STATION, MARYLAND.

THILL-COUPING.

SPECIFICATION forming part of Letters Patent No. 450,418, dated April 14, 1891.

Application filed October 9, 1890. Serial No. 367,530. (No model.)

To all whom it may concern:

Be it known that I, WILLIAM C. MOLER, a citizen of the United States, residing at Claggett's Station, county of Washington, Maryland, have invented certain new and useful Improvements in Thill-Couplings, of which the following is a specification.

My invention relates to thill-couplings, and has for its object to provide simple and efficient means for securing and holding the parts together against accidental or other displacement; and it consists in a construction and arrangement of parts substantially as hereinafter more particularly pointed out.

15 Referring to the accompanying drawings, Figure 1 is a perspective view illustrating my invention applied to one form of coupling, and Fig. 2 is a side view of the same. Fig. 3 is a sectional view.

20 In the drawings, A represents the axle or other part to which the coupling is attached. The coupling shown consists of the clip B, secured to the axle A in the usual manner, and having formed integral therewith ears C, between which is supported the thill-iron D. This thill-iron is united to the ears by a removable bolt E, having a tapering head fitting in a large or recessed opening on the outside of one of the ears C, so that the bolt and side 25 30 of the opening are flush with each other when the bolt is in place, and the small end of the bolt preferably projects a short distance beyond the other ear, so that the bolt can be readily pushed out when it is desired to separate the parts. It is desirable that this bolt while being readily removable may be securely held in position against accidental displacement, and to accomplish this is the principal object of my invention. Secured to the

40 outside of one of the lugs C is a guard-plate F, and this is preferably united by a rivet or bolt f, which may be hammered or otherwise secured against displacement. This guard-plate is made with a substantially straight side f', which is made to conform to and normally bear against the axle A, as shown in Fig. 2. From this straight side extends the curved side f'', and this curve is substantially concentric with the pivot F of the plate. The 45 50 upper portion of the plate is extended to form

a knob or portion f³, which serves as a handle to move the plate from one position to another.

Through the body of the plate F is made a perforation G, which is preferably substantially the same size as the head of the bolt E, and is arranged so that when the guard is raised into the position shown in Fig. 1 this opening corresponds exactly with the opening in the side of the lug and allows the bolt-head 55 60 to be pushed through the opening and the bolt removed. When, however, the guard is removed from any position except the one indicated, the bolt will be securely locked and held in position.

65 The guard-plate being pivoted at one side of the bolt-hole and being of the shape and configuration described has the tendency to remain in the position shown in full lines in Fig. 2, and no ordinary jolt, jar, or blow will 70 throw it materially out of this position, and if it is perchance thrown out of position the bolt cannot be removed or fall out accidentally until the opening G coincides exactly with the opening in the side of the lug and is 75 directly over the bolt-head, and this is a contingency which is almost impossible to happen. It will thus be seen that the guard-plate, which is simply a piece of metal having the configuration described and provided with 80 the perforation, as indicated, is exceedingly cheap, that it can be applied to thill-couplings already in use without material change, and that when applied it securely locks the bolt, holding the thill-iron in position against 85 any accidental displacement, but at the same time permits the ready removal of the bolt when desired.

As a still further precaution I sometimes add the shield H, which is pivoted to the stud 90 or bolt f and normally covers the opening G in the plate, a stud or pin h holding it in position over the opening, but permitting its being swung out of the way to remove the bolt. When this shield is used, not only must the 95 hole in the plate coincide with the head of the bolt when it is to be removed, but the shield must also be lifted out of the way.

While I have shown and described my invention as applied to one particular form of 100

thill-coupling, it is evident that it may be applied to other forms without departing from the principles of its construction.

What I claim is—

- 5 1. The combination, with a thill-coupling the lugs of which support a bolt flush with the outside surface of one of the lugs, of a guard-plate pivotally mounted on the lug at one side of the bolt, said guard-plate being provided
- 10 with an opening corresponding to the opening in the lug, substantially as described.
- 15 2. The combination, with the thill-coupling having the lugs through which passes a bolt the head of which is flush with the outside of one of the lugs, of a guard-plate pivotally mounted on the outside of the lug, said guard-plate having a straight side and a curved side

and projection at the upper end, and a perforation through its body corresponding to the size of the bolt-head, substantially as described.

- 20 3. The combination, with the thill-coupling having the lugs through which passes a bolt, of a guard-plate pivoted to the side of one of the lugs and having an opening, and a shield 25 for covering the opening pivotally attached to the guard-plate, substantially as described.

In testimony whereof I have signed my name to this specification in the presence of two subscribing witnesses.

WILLIAM C. MOLER.
